CLAIM

An ornamental design for a poultry feeder tube, as shown and described.

DESCRIPTION

FIG. 1 is a perspective view of a poultry feeder tube according to the invention;

FIG. 2 is a side view thereof;

FIG. 3 is a top view thereof;

FIG. 4 is a bottom view thereof; and,

FIG. 5 is a cross-section view of the poultry feeder tube, taken along line 5-5 indicated in FIG. 2.
